JEWELLED LIPSTICK CASE

Bertram Schwartz, Croton-on-Hudson, N. Y.

Application October 20, 1952, Serial No. 21,903

Term of patent 3½ years

(Cl. D86—10)

To all whom it may concern:

Be it known that I, Bertram Schwartz, a citizen of the United States and a resident of Croton-on-Hudson, county of Westchester, and State of New York, have invented a new, original, and ornamental Design for a Jeweled Lipstick Case, of which the following is a specification, reference being had to the accompanying drawings, forming part hereof, and in which:

Fig. 1 is a side elevational view of a jeweled lipstick case, showing my new design.

Fig. 2 is another side elevational view at 90 degrees to Fig. 1.

Fig. 3 is a top plan view upon an enlarged scale as compared to Figs. 1 and 2.

The characteristic feature of the design resides in the portions shown in full lines.

I claim:

The ornamental design for a jeweled lipstick case, as shown and described.

BERTRAM SCHWARTZ.
